Edward M. Otis, Syracuse, N. Y., assignor to
Onondaga Pottery Company, Syracuse, N. Y.,
a corporation of New York

Application June 28, 1952, Serial No. 20,394

Term of patent 14 years

(Cl. D44—15)

To all whom it may concern:

Be it known that I, Edward M. Otis, a citizen of the United States, residing at Syracuse, State of New York, have invented a new, original, and ornamental Design for a Dinner Plate or Similar Article, of which the following is a specification, reference being had to the accompanying drawing, forming part hereof.

The drawing is a plan view of a plate of conventional configuration showing my new design. The dominant feature of the design resides in the ornamentation shown and arranged on the plate.

I claim:

The ornamental design for a dinner plate or similar article, as shown and described.

EDWARD M. OTIS.
